WILLIAM H. TERWILLIGER, OF AMSTERDAM, NEW YORK, ASSIGNOR TO FREDERICK KLEIN, TRUSTEE.

SHUTTLE FOR SEWING-MACHINES.

1,253,646.

Specification of Letters Patent. Patented Jan. 15, 1918.

Application filed May 29, 1915. Serial No. 31,145.

To all whom it may concern:

Be it known that I, WILLIAM H. TERWILLIGER, a citizen of the United States, and resident of Amsterdam, county of Montgomery, and State of New York, have invented certain new and useful Improvements in Shuttles for Sewing-Machines, of which the following is a specification.

My invention relates more particularly to 10 a shuttle for use in lock stitch sewing machines of the type described in Patent No. 1,049,430 to C. H. Wilkes, January 7, 1913. This type of machine is particularly adapted for making gloves and produces a lock 15 stitch that is adapted to sew the glove fingers and other parts with a flat seam thereby producing what are called pique gloves. In this machine the parts of the glove to be sewed are supported upon a spindle or 20 finger table small enough to enter the glove finger and the lock stitch is produced by drawing a loop of the needle thread through the spindle and turning it over a shuttle or looper located outside of and at the lower 25 end of the spindle.

A reciprocating thread hook is adapted to draw the needle thread through the spindle and into position to be intercepted by the shuttle hook, the latter then throwing the loop to the opposite side so as to 30 inclose the bobbin thread for forming the lock stitch in the usual manner.

In machines of this type it is preferable that the bobbin thread be taken from the 35 shuttle at the rear in order that it shall not interfere with the thread hook.

It is also desirable, at times, to use a flat ball of thread in the shuttle instead of having the thread wound upon the usual bobbin 40 spool thus saving something in labor and time which, of course, enter as factors in the cost of production.

The object of my invention is to produce a simple shuttle of the character indicated 45 in which either ball thread or a bobbin spool containing thread may be used as desired, means being provided for adjusting the tension in either case. A further object is to provide means for readily removing or inserting the bobbin or the ball of thread in the looper or shuttle, this being preferably accomplished by providing a removable cover plate and means for locking it in place upon the body portion of the looper.

55 One form or preferred construction of my

improved shuttle is represented in the accompanying drawings of which Figure 1 shows parts of a glove sewing machine with the shuttle in place; Fig. 2 shows the shuttle separately, back view; Fig. 3 is an edge view 60 looking toward the left in Fig. 2; Fig. 4 is a view similar to Fig. 2 but with the cover section removed; Fig. 5 is the cover section, inside view; Fig. 6 is an enlarged sectional view along the line 6—6 of Fig. 2; 65 Fig. 7 is a section (enlarged) on line 7—7 of Fig. 2 and Fig. 8 is partial section (enlarged) on line 8—8 of Fig. 2.

Referring to the drawings 1 represents the table or bed of the sewing machine upon 70 which is mounted a spindle 2, the top of which at 3 is adapted to support the goods being sewed, 4 is the needle rod and 5 is the needle carrying one of the threads 6 required to form the lock stitch. A bracket 7 75 is secured to the underside of the bed 1 and is adapted to support a thread hook guide 8 having mounted therein a reciprocating thread hook 9 the thread hook being adapted to be reciprocated through the spindle 2 80 to grasp a loop of the needle thread 6 formed when the needle 5 penetrates the goods and passes down into the upper end of the spindle 2. After the thread hook 9 catches the loop of the needle thread it is 85 drawn down to the position indicated in Fig. 1 of the drawings in which position it is adapted to be taken up by the hook 10 of the shuttle which carries the other thread 11 required to complete the lock stitch. The 90 shuttle hook 10 is preferably formed integral with the shuttle member 12 and is slightly inclined thereto substantially as indicated in the drawings. The body of the hook member 12 is provided with a circular opening 13 which as indicated is eccentric of the outer bearing surface of the hook member. A portion of the outer periphery of the hook member forms a bearing surface whereby the shuttle is adapted to oscillate in 100 a circular bearing at 14 in the bracket 7. The circular opening 13 on the front face of the hook member 12 is provided with an inwardly projecting flange 15 adapted to assist in retaining the bobbin or flat ball of thread 105 in place. The opposite face of the hook member 12 is adapted to receive a cover member 16 which is provided with a recess 17 adapted to coincide with the circular opening 13 in the hook member 12 to form 110

a cavity or container for the bobbin 18 as shown in Fig. 6 or a flat ball of thread 19 as shown in Fig. 7 of the drawing. The cover member 16 and hook member 12 are adapted 5 to be secured together, preferably by a form of bayonet joint consisting of two studs or pins 20 having heads adapted to enter buttonhole shaped recesses 21 in the body member 12, the recesses 21 being undercut as indicated in Fig. 6 so as to retain the two members in close engagement. It will be understood that to remove the cover member from the hook member it should be turned toward the left as indicated in Fig. 2 of the 10 drawings. Since the shuttle as a whole is oscillated in order to carry the needle thread loop over the bobbin thread in forming the lock stitch the cover 16 is likely to be displaced in the buttonhole slots 21. To avoid 15 the possibility of this occurring I have provided a locking bolt 22 the outer end of which is adapted to enter a small hole 23 in the cover 16 and thus lock the cover member so that it cannot be rotated relative to 20 the hook member during the normal operation of the shuttle. When it is desired to remove the cover, however, the bolt may be pressed back against the action of the spring 24 so as to remove the end of the bolt from 25 the hole 23 and then the cover can be turned toward the left and separated from the hook member 12 so as to permit replacing the bobbin or replenishing the supply of thread in 30 the shuttle.

35 The cover member 16 is preferably provided with two outlet holes, one hole 25, central of the recess 17, is adapted for the passage of the shuttle thread when a flat ball of thread is used and the other hole 26 is 40 adapted for use to withdraw the thread when a bobbin spool is used in the shuttle. The cover member 16 is also provided with a resilient tension or guide finger 27 secured to the outer face thereof by a screw 28 and 45 provided with a hole at 29 through which the shuttle thread is drawn from either of the holes 25 or 26. The hole 29 is preferably located concentric of the shuttle or at the axis of oscillation thereof.

50 As will be seen in Figs. 6, 7 and 8, the tension finger 27 is spaced from the outer recessed face of the cover member 16 and is located in the recess 30 on the outer face 55 of the cover. The space between the tension finger 27 and the recessed face of the cover is preferably made adjustable so that the tension on the shuttle thread may be varied as desired. This adjustment is obtained in the present instance by means of 60 a set screw 31 (see Fig. 8) the point of which is adapted to rest against the underside of the tension finger 27 and by moving screw in or out it will be readily understood that the position of the outer end of the finger 27 may be varied. By this means the

tension or pressure upon the thread may be varied.

A recess 32 is provided in one edge of circular opening 13 adjacent to the cover for the passage of the thread when a bobbin 70 spool is used.

The operation of the shuttle will be understood from the description of the device in view of the fact that the general method of forming a lock stitch is well known but 75 the present form of my device is particularly adapted to the glove sewing machines of the type hereinbefore referred to.

During the operation of the machine the bar 33 is adapted to be oscillated by suitable 80 mechanism (not shown) and thereby oscillate the shuttle so that the hook 10 removes the thread loop from the thread hook 9 after the same has been drawn down the spindle 2, the beginning of this operation 85 being indicated in Fig. 1 of the drawings. The shuttle is then oscillated about two-thirds of a revolution and the loop is passed between the shuttle and the member 33, sliding off the end opposite the hook, after 90 which the loop is free to be drawn up through the goods to form the lock stitch.

It will be understood that various modifications of the specific detail of construction may be made without departing from 95 the spirit and scope of the invention.

I claim:

1. In a shuttle for lock stitch sewing machines, the combination of a loop hook member having slots, a cover element having pins adapted to engage said slots and lock therewith on axial rotation of said cover member. 100
2. In a shuttle for lock stitch sewing machines, the combination of a loop hook element having slots, a cover element having pins adapted to engage said slots and means to lock said cover element in position. 105
3. In a shuttle for lock-stitch sewing machines, the combination of a loop hook element recessed to receive the bobbin spool, a cover element having an aperture through which the thread is adapted to be drawn, said cover element having a recess, a tension device in said recess having a hole 110 through which the thread is passed and means bearing on the inner face of said device for varying the tension thereof.
4. In a shuttle for lock-stitch sewing machines, the combination of a loop-hook member provided with a flanged circular opening arranged eccentrically to the bearing surface of said hook member having slots, a cover member provided with a recess adapted to coincide with the circular opening of 125 said hook member, and having pins adapted to lock with said slots whereby said cover is secured to said hook member, and a resilient locking bolt for holding the cover in secured position. 130

5. In a shuttle for lock-stitch sewing machines, the combination of a loop hook member provided with a flanged circular opening arranged eccentrically to the bearing 5 surface of said hook member, a cover member provided with a recess adapted to coincide with the circular opening of said hook member, pin and slot means for securing said cover to said hook member and a locking bolt for holding the cover in secured position.

6. In a shuttle for lock-stitch sewing machines the combination of a loop hook member provided with a flanged circular opening arranged eccentrically to the bearing 15 surface of said hook member, a cover member provided with a recess adapted to coincide with the circular opening of said hook member, pin and slot means for securing 20 said cover to said hook member, a locking bolt for holding the cover in secured position said cover being provided with a hole for the passage of the thread, a resilient finger secured to the outside of the cover and 25 provided with a hole concentric of the shuttle, the thread being led from the hole in the cover through the hole in said finger and means for adjusting the position of said finger whereby the tension upon the thread 30 may be varied.

7. In a shuttle for lock-stitch sewing machines the combination of a loop hook member provided with a circular opening having an annular flange at one face, a cover member 35 adapted to be secured to the other face of said hook member, said cover being provided with a recess adapted to coincide with the circular opening of said hook member to form a cavity for the thread, the cover being provided with a hole through which the thread may be drawn, a tension guide finger on said cover, a resiliently mounted locking bolt for said cover and means for adjusting said finger to vary the tension on the 40 thread.

8. As an article of manufacture, a shuttle for lock-stitch sewing machines adapted for holding either a bobbin or a flat ball of thread, comprising a loop-hook member provided with a circular opening flanged at one 45

edge, a cover provided with a recess adapted to coincide with the circular opening in said hook member, means for securing the cover to the hook member, said cover being provided with a hole central of said cover recess for the thread to pass through when using a flat ball, and with a marginal hole for the thread to pass through when using a bobbin in said shuttle, a tension finger on said cover having a hole concentric of the shuttle through which the thread from the shuttle is to be drawn and means for adjusting the tension on said finger.

9. As an article of manufacture a shuttle for lock-stitch sewing machines adapted for holding either a bobbin or a flat ball of thread, comprising a hook member, a recessed cover provided with a hole for the bobbin thread and a hole for the ball thread, means for securing the cover to said hook member, means for locking the cover from relative movement when so secured, a tension finger thread guide on said cover and means for regulating the tension thereof.

10. As an article of manufacture, a shuttle for lock-stitch sewing machines adapted for holding either a bobbin or a flat ball of thread, comprising a loop hook member having a circular opening, a cover provided with a recess adapted to coincide with the circular opening in said hook member, means for securing the cover to the hook member, said cover being provided with a hole central of said cover recess for the thread to pass through when using a flat ball, and with a marginal hole for the thread to pass through when using a bobbin in said shuttle, a tension finger on said cover having a hole concentric of the shuttle through which the thread from the shuttle is to be drawn and means for adjusting the pressure of said finger.

In witness whereof I have hereunto set my hand in the presence of two subscribing witnesses.

WILLIAM H. TERWILLIGER.
